UNITED STATES PATENT OFFICE

LOUIS COHEN, OF WASHINGTON, DISTRICT OF COLUMBIA, ASSIGNOR, BY MESNE ASSIGNMENTS, TO FEDERAL TELEGRAPH COMPANY, A CORPORATION OF CALIFORNIA

RADIO RECEIVING SYSTEM

Application filed October 2, 1925. Serial No. 60,120.

This invention relates to an improvement in antennæ for the reception of radio signals.

The object of the invention is a novel and improved form of antenna resonantly responsive simultaneously to a number of different frequencies.

Another object is to provide method and means for the simultaneous operation of several receivers on the same antenna.

10 In the reception of radio signals, the elements required are an antenna or an energy collector, tuned circuits, detector and amplifier. For each individual receiver a separate antenna is required. The continuous increase 15 in the number of receivers used for broadcast reception necessitates a corresponding continuous increase in the number of antennæ so that even at the present time in each large apartment building housing many dwellers, 20 the roof is frequently covered by a network of antennæ. Each individual antenna means expense in installation and also requires attention and frequently difficulties arise in accommodating all who desire to install antennæ on the roof of the same building for the 25 operation of the individual receivers. As time goes on and the use of radio becomes still more widespread, the situation is sure to become more aggravated.

30 This invention offers a solution to the problem by providing a method whereby a single antenna may be used for the simultaneous operation of many receivers, each selecting the particular signals it is desired to receive.

35 This is accomplished by the use of an antenna which is resonantly responsive simultaneously to a number of frequencies within a predetermined range of frequencies, and if the different frequencies for which the antenna

40 is thus tuned are close together the antenna will act as an efficient energy collector for practically all the frequencies within the extreme limits of the frequencies for which the antenna is tuned. A number of receivers

45 can then be coupled to the antenna and each receiver tuned to select the particular signal desired. Such an antenna is particularly adapted for use on large apartment buildings adjusted to be in resonance for frequencies 50 within the broadcasting range, and thus make

it available for broadcast reception by all the tenants in the building. Further, since only one antenna suffices for an entire building, more space will be available to build an antenna covering a larger area which would be 55 a more efficient energy collector.

In order that the invention may be more fully understood, attention is directed to the accompanying drawings forming a part of the specification, in which :

60 Figure 1 shows an embodiment of my invention in which the tuning elements of the antenna are coupled to each other through inductances and the various receivers are coupled to the antenna inductively; Fig. 2 is another embodiment of my invention in which the tuning elements of the antenna are coupled through condensers, and the various receivers are also coupled to the antenna through condensers. 65

70 Having particular reference to the drawings in which like reference characters designate similar parts, in Fig. 1, the antenna 1, preferably a horizontal type of large area, is connected through the lead 2 to the series of coupling inductances 3, 4, 5, and 6, the circuits system A, and ground 21. If the antenna is placed on the roof of a building, the lead 2 is made long enough so as to bring the coupling inductance coils to any 80 desired level of the building. Each of the coupling coils 3, 4, 5, and 6 is shunted by a very small condenser 43 so that when any inductance coil is opened or disconnected the antenna circuit will not be broken. A series 85 of tuning receiving circuits indicated by 23, 24; 25, 26; 27, 28; and 29, 30; and associated detectors and amplifiers designated by 44, are coupled to the coupling inductances in the antenna circuit. The circuit system A 90

which consists of a series of similar sections, each comprising a series inductance and a shunt circuit of an inductance and capacity in parallel, functions to effect the multiple tuning of the antenna system. In my copending application Serial No. 53,714, filed August 31, 1925, I have shown that a circuit system as that indicated by A, responds resonantly 95 to a number of frequencies, the extreme fre- 100

quencies for which the system is in resonance being given by the following formula:

$$f_1 = \frac{1}{2\pi\sqrt{L_2 C_2}}$$

$$f_n = \frac{1}{2\pi\sqrt{L_2 C_2}} \sqrt{1 + \frac{4L_2}{L_1}}$$

where L_1 designates the series inductance, 10 and L_2 and C_2 the inductances and capacity of the shunt circuit. It is evident that the range of frequencies for which the system is 15 in resonance depends on the ratio of $\frac{L_2}{L_1}$, and this ratio can be fixed to cover any desired 20 range, which may be the broadcasting range now in use. The number of frequencies within that range for which the system is 25 in resonance is determined by the number of sections used. By increasing the number of sections the system will be in resonance for a larger number of frequencies and thus bring the resonance frequencies closer together which would give the effect of approximate tuning for all the frequencies within the range for which the system is 30 adjusted. This antenna system, therefore, will respond resonantly to signals of all frequencies within a certain range of frequencies. 35 The several receiving circuits are each tuned to a frequency of a particular signal whose frequency is within the range of frequencies for which the antenna system is tuned. By this arrangement a number of receivers may be connected up to one antenna, each one operating independently and selecting the particular signal desired.

For purposes of illustration I have shown 40 in the figure only four receiving circuits connected to the antenna, but this should not be taken as a limitation upon the system for the method is well adapted for use in the operation of a large number of receivers connected to the same antenna. Also, the tuning circuit system A is shown here as comprising 45 five sections. This again is merely illustrative. The more sections used the closer approach to tuning for all frequencies within a given range is obtained and the more 50 satisfactory the system will operate.

Figure 2 is similar to Fig. 1 except for 55 modifications in the matter of couplings. The receiving circuits are coupled through condensers to the antenna. Each of the receiving circuits 23, 24, 25, 26; 27, 28; and 29, 30; are connected through small condensers across a series condenser in the antenna. This type of coupling may be called electro- 60 static coupling which takes the place of the electromagnetic coupling or inductive coupling shown in connection with Fig. 1. Also, in the tuning circuit system A, the shunt elements are connected through small condensers 65 instead of inductances as in the case of

Fig. 1. The principles of operation of this system are similar to those described in connection with Fig. 1.

What I claim and desire to secure by Letters Patent of the United States is as follows: 70

1. In a multiplex radio receiving system comprising an antenna-ground circuit, a circuit system connected in series with the said antenna, said circuit system consisting of a number of sections, each section comprising a series inductance and a pair of tuned circuits, each tuned circuit including an inductance shunted by a condenser, said tuned circuits all being connected together and disposed in series in said antenna and ground circuit to 75 effect a multiple tuning of the antenna, a plurality of separate receiving circuits associated with the said antenna and independent of the aforesaid sections, each of said receiving circuits being adjusted for resonance for one of the frequencies within the range of frequencies for which the antenna system is tuned, and separate detectors and amplifiers associated with each of said receiving circuits. 80

2. In a multiplex radio receiving system comprising an antenna, a circuit system associated with the said antenna, said circuit system comprising a number of sections, each section consisting of an impedance element and two loop circuits, said loop circuits being directly connected together at one end and having their opposite ends connected through said impedance element with the adjacent sections having a loop circuit in common to effect multiple tuning of the antenna, several additional inductances in series in the antenna circuit and a separate receiving circuit coupled to each of the said additional inductances, each of the said receiving circuits being tuned to a frequency within the frequency range for which the antenna system is tuned and separate detectors and amplifiers associated with each of the receiving circuits, said receiving circuits each being independent of the sections of said circuit system. 100

3. In a multiplex radio receiving system comprising an antenna, a circuit system associated with the said antenna, said circuit system comprising a number of sections, each section consisting of an impedance element and two loop circuits, said loop circuits being directly connected together at one end and having their opposite ends connected through said impedance element with the aforesaid sections having a loop circuit in common and related to each other to effect multiple tuning of the antenna, several additional inductances in series in the antenna circuit, each of the said additional inductances being shunted by a condenser, and an independent receiving circuit separately coupled to each of the said additional inductances, each of the said receiving circuits being tuned to a frequency within the range of frequencies for which the antenna system is tuned and separate de- 110

tectors and amplifiers associated with each of the receiving circuits.

4. In a system for the reception of radio signals comprising an antenna, a circuit system and ground, all connected in series constituting the antenna circuit, the said circuit system comprising a chain of independent circuits with each of the elements in said circuits tuned to a certain frequency and coupled electrically one to the other by means of impedance units, the electrical constants of the elements of each of the said independent circuits and the couplings between them being so adjusted as to make the said antenna circuit system simultaneously resonant for several frequencies, several independent receiving circuits separately coupled to the said antenna, and each of the said independent receiving circuits being adjusted in resonance for one of the frequencies for which the said antenna circuit system is tuned.

In testimony whereof I affix my signature.
LOUIS COHEN.
